UNITED STATES PATENT OFFICE.

SOLOMON LACASSE, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

EYE PROTECTOR.

Application filed July 30, 1924. Serial No. 729,148.

The present invention relates to an improved eye protector or goggle and has particular reference to a goggle having a lens which may be placed into and removed from 5 operative position quickly and readily when desired.

An important object of the invention is to provide an eye protector of this character including an eye cup adapted to receive a 10 lens and having means disposed on the interior of the cup abutting against the lens to hold the same in operative position and which may be removed from the cup when it is desired to replace or remove the lens.

15 A still further object of the invention is to provide an eye protector of this character wherein the lens may be removed when desired, while at the same time the eye protector can be constructed from a minimum 20 number of parts and which will be comparatively inexpensive but rugged.

Other objects and advantages of the invention will become apparent from the course of the following description.

25 In the drawings, wherein like numerals are employed to designate like parts throughout the same:

Figure 1 is a front elevation of the complete goggle.

30 Figure 2 is a section through one of the cup members.

Figure 3 is a perspective view of the lens retaining means.

35 Figure 4 is a fragmentary perspective of the eye protector illustrating a lens retaining means prior to its insertion into operative position.

In the drawings, wherein for the purposes 40 of illustration is shown the preferred embodiment of the invention, the numeral 5 designates an eye protector in its entirety and comprises the eye cups 6 having a lens therein 7, the said cups being connected by means of suitable bridge 8 or the like, and 45 having a head band 9 to hold the same in place upon the user's head.

In the past, many attempts have been 50 made to construct an eye protector wherein the lenses are easily removed and in which the lenses will be held firmly in position and guarded against accidental displacement when the protector is in use. The present construction embodies means wherein the lenses can be easily removed while at the

same time, when in use the lens retaining 55 members prevent accidental displacement or rattling of the lens.

The cup 6 is provided with the flange 10 against which the lens 7 is adapted to abut on the inside of the said cup as clearly 60 shown in Figure 2. The interior of the cup is also provided with the shoulder 11, shown in Figure 2, which shoulder extends from the diametrically opposed points of the cup 12 so that the portion 13 of the cup has no 65 shoulder, as is clearly shown. The bridge 8 is anchored to the cups by means of the members 14 which are sufficiently spaced from the flange 10 to permit of the insertion of the lens 7 and the lens retaining member 15. 70 The lens retaining member 15 is formed from preferably a single length of metallic wire which is bent to form the operating finger engaging portions 16. The ends 16 are spaced to permit the ring to be contracted 75 so as to permit of the insertion within the cup 6. The finger engaging portions 16 are bent to form the links 17 which are disposed in a plane substantially parallel to the ring portion of the retaining member so that the 80 links 17 will engage the shoulder 11 on the inside of the cup when in operative position. To assemble the goggle the lens 7 is placed on the inside of the cup and is rested upon the flange 10. The ring, or lens retaining member 85 15 is then placed within the cup in contracted position so that it will follow between the member 14 and the lens. The easiest way is to slide the finger engaging portions down at the end 13 and after the 90 ring portion 15 is in engagement with the lens, the whole retaining member is twisted around until the links 17 engage the shoulder 11, thus preventing accidental displacement 95 of the lens.

Of course, it is desirable to form the retaining member from resilient material so that there will be a slight pressure on the lens at all times. If it is desired, a washer may be used between the lens and flange or the 100 lens and retaining member, or both, so as to prevent any possible movement of the lens, or chipping of the edges thereof.

It is to be understood that the form of the invention herewith shown and described 105 is to be taken as the preferred embodiment of the same and that various changes in the shape, size and arrangement of parts may be

resorted to without departing from the spirit of the invention or the scope of the subjoined claims.

Having thus described my invention, I 5 claim:—

1. In a device of the character described, a tubular eye cup having a lens seat at its outer end having a shoulder on the inside of the tube extending a part way only there- 10 around parallel to the lens seat and spaced therefrom intermediate the ends of the eye cup and having also a projection extending into the cup on the side opposite the shoul- 15 der, and a spring having a portion lying against the lens, a portion at right angles to the first portion and extending along the inside wall of the eye cup; a portion parallel to the first portion and engaged by the shoul- der on the inside of the tube of the eye cup,

and a portion extending under the projec- 20 tion.

2. In a device of the character described, a tubular eye cup having a lens seat at its outer end having a shoulder on the inside 25 of the tube parallel to the lens seat and spaced therefrom intermediate the ends of the eye cup, a bridge connection on one side of the eye cup having a portion projecting into the tube thereof, a spring having a portion lying against the lens and extending 30 under the projection of the bridge connection into the eye cup; a portion at right angles to the first portion and extending along the inside wall of the eye cup, and a portion parallel to the first portion engaged by the 35 shoulder on the inside of the tube of the eye cup.

SOLOMON LACASSE.
